UNITED STATES PATENT OFFICE.

ANTHONY TRAVERS, OF FAIRHAVEN, MASSACHUSETTS.

DESIGN FOR A RADIATOR-CAP ORNAMENT.

59,878.

Specification for Design.

Patented Nov. 29, 1921.

Application filed May 17, 1921. Serial No. 470,480. Term of patent 14 years.

To all whom it may concern:

Be it known that I, ANTHONY TRAVERS, a citizen of the United States of America, residing at Fairhaven, in the county of Bristol and State of Massachusetts, have invented a new, original, and ornamental Design for Radiator-Cap Ornaments, of which the following is a specification, reference being had to the accompanying drawings, forming a part hereof.

The figure is a perspective view showing my new design.

I claim:

The ornamental design for a radiator cap ornament as shown.

ANTHONY TRAVERS.

Witnesses:
